FREE STANDING FIREPLACE

Glen D. Crownover, Santa Rosa, Calif., assignor to Malm Fireplaces, Inc., Santa Rosa, Calif.

Filed Aug. 30, 1972, Ser. No. 284,745

Term of patent 14 years

Int. Cl. D23—03
U.S. Cl. D23—97

Fig. 1

Fig. 2

Fig. 3

Fig. 4

Fig. 5

FIG. 1 is a front elevation view of a free standing fireplace showing my new design.

FIG. 2 is a side elevation view thereof.

FIG. 3 is a top view thereof.

FIG. 4 is a rear elevation view thereof; and

FIG. 5 is a bottom view thereof.

A characteristic feature of the ornamental design of the present invention is its curved base.

I claim:

The ornamental design for a free standing fireplace, as shown and described.
